UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 19,814, dated May 6, 1890.

Application filed April 11, 1890. Serial No. 347,539. Term of patent 3½ years.

To all whom it may concern:

Be it known that I, JAMES L. FOLSOM, a citizen of the United States, and a resident of the city of Brooklyn, in the county of Kings 5 and State of New York, have invented a new and original Design for Carpets, of which the following is a specification, reference being had to the accompanying photograph, which forms a part of the same.

10 The invention relates to a design to be worked into or upon surfaces, such as carpets or similar fabrics; and it consists in the novel configuration and grouping of figures herein specifically shown and claimed.

15 The accompanying photograph is a face view of a carpet showing my new design.

My design consists of a body A and a border B.

20 The body A contains three leading features: first, large and deeply serrated conventionalized leaf forms; second, conventionalized circular flower forms, and, third, groups or masses of small gems or flower forms. These 25 are disposed over the face of the design in a more or less irregular manner. Between them

are scattered a few small sprays and leaf and flower forms. The large leaf forms are ornamented with small sprays bearing gems.

The border B is composed of an inner margin of ornamental design, a main part similar in its leading features to the body A. Outside of these is a band of small flower forms or gems bounded on one side by an undulating line of coral-like sprigs and on the other by parallel undulating lines. On the outer margin are inconspicuous conventionalized flower forms.

What I claim as new, and desire to secure by Letters Patent, is—

1. The design for a carpet, consisting of the body A, substantially as shown.
2. The design for a carpet, consisting of the border B, substantially as shown.
3. The design for a carpet, consisting of the body A and the border B, substantially as shown.

JAS. L. FOLSOM.
